Primary Examiner — Joseph Kukella
 Assistant Examiner — Molly Loch(57) **CLAIM**

The ornamental design for a watch case as shown and described.

DESCRIPTION

1. Watch case
- 1.1 : Perspective
- 1.2 : Front
- 1.3 : Left
- 1.4 : Right
- 1.5 : Back
- 1.6 : Top
- 1.7 : Bottom

The broken lines show portions of the watch case that form no part of the claimed design. The characteristic features of the design lie in the shape of the main body of the watch case. The product as a whole is used as a watch case; the use of the partial design is the main body of the watch case.
